UNITED STATES PATENT OFFICE.

GUSTAV BENISCH, OF BROOKLYN, NEW YORK.

UNIVERSAL ADJUSTABLE PIVOT FOR SWINGING DOORS.

1,147,330.

Specification of Letters Patent. Patented July 20, 1915.

Application filed February 15, 1915. Serial No. 8,394.

To all whom it may concern:

Be it known that I, GUSTAV BENISCH, a citizen of the United States of America, and resident of the borough of Brooklyn, county of Kings, and State of New York, have invented certain new and useful Improvements in Universal Adjustable Pivots for Swinging Doors, of which the following is a specification.

10 This invention relates to improvements in universal adjustable pivots, and particularly such pivots for doors of granite mausoleums or other such permanent structures exposed to the elements. These doors as heretofore constructed were usually set on a bronze saddle and swung inwardly, so that there existed, because of the nature of the door and the improper adjustment of the hinges, an exposed joint which would allow rain to beat 20 or seep into the structure, and thereby gradually deteriorate the same and endanger its permanence.

The object of the present invention is to provide in a door adapted to swing outwardly and to close against permanent abutments or other suitable doors a universal adjustable pivot, so that any inaccuracy in the drilling of pivot holes before the granite is set may be corrected, and thereby establish 30 close joints between the door and frame. The adjustment may also be used on a door swinging inward or on any other type of door.

With this and other objects in view, my 35 invention consists of the novel features, construction and arrangement of parts herein-after more fully described and pointed out in the claims.

In the drawings, Figure 1 is a front elevational view of a double door embodying my invention; Fig. 2 is a horizontal section of the same; Fig. 3 is a vertical section thereof; Fig. 4 is an enlarged vertical section of my universal adjustable pivot; Fig. 40 5 is a horizontal section of the same on the line 5--5 of Fig. 4; Fig. 6 is a sectional view of a door and frame with a separate bronze saddle and lintel; Fig. 7 is a plan of a modified form of universal adjustable 45 50 pivot; and, Fig. 8 is a sectional view of a modified jamb.

Referring to the drawings, and more particularly to Figs. 1-5 thereof, a door 1 is provided having a rounded end as shown in Fig. 6, or otherwise suitably shaped, such as

shown for instance in Fig. 8, fitting in the jamb 2 of a door-frame, so that the same may freely swing and at the same time form a tight joint when closed. The door illustrated swings outwardly, but this is not essential to the operation of my invention. Holes are drilled in the platform 4 of the door and lintel 5 at either side thereof when there are two doors, and at one side when there is only one door, and bronze rings 6 provided on their inner surface with teeth are secured by babbetting or other suitable means into the said holes before the granite or concrete is set. The frame for the door is then set up in this form, and eccentric 70 bronze rings 7 having their inner and outer surfaces toothed to correspond with the toothed inner surface of the bronze rings 6, are placed therein, and a second eccentric ring 8, having its outer surface toothed, is 75 placed in the said ring 7. The exact pivot point for the door is then determined by arranging the said rings with respect to each other and with respect to the jambs of the door-frame, so that the recess 9, formed by 80 the hole in the ring 8, coincides with the said pivot point. When the rings are so arranged, the doors are set thereon, and bolts or pivots 10 provided in recess 11 in the door are slid into the same and secured in place 85 by screws 12.

In the form shown in Fig. 7, disks 13 having apertures 14 therein are secured into the lintel and platform, before the same are set, in the manner above described. The said 90 apertures and disks may be square (as shown), rectangular, polygonal, or other suitable shape, into which a plate 15 of corresponding shape is adapted to be fitted. When the structure is set up, the exact pivot 95 points are ascertained on the plates 14 and holes 16 are drilled therein accordingly for receiving the bolts or pivots 20 of the door.

Where a saddle or a saddle and lintel of a separate structure and material, for instance 100 of bronze, are provided for the door-frame, the holes for the rings, or for the pivots, are drilled in the separate saddle and lintel, as shown at 21 and 22 in Fig. 6. If desired, the bronze rings 8 or the disks 13 may be made 105 integral with the saddle and lintel of bronze with the same result, or in other words, apertures corresponding in shape to the eccentric rings 7 and disks 14 may be provided in the saddle and lintel. The checks on back of the 110

saddle or on both the saddle and lintel may be omitted if desired, so that the door may swing inward, or both inward and outward.

It is obvious that with my universal adjustable pivot a very exact fitting and operating joint is provided for such pivoted doors, so that there can be no crevices where-in water or the like may leak into the structure.

10 I have illustrated and described preferred and satisfactory embodiments of my invention, but it is obvious that changes may be made therein and that the same may be used in other constructions without departing 15 from the spirit and scope thereof, as defined in the appended claims, and other materials than bronze and granite may be used as well.

I claim:—

1. An adjustable pivot comprising a rigidly secured member provided with an aperture, and a second member interlocking with said rigid member, and provided with a pivot point adjustable in any direction in a plane perpendicular to the axes of the members and adjustable in respect to said rigid member.

2. A universal adjustable pivot, comprising a rigidly secured member, provided with

an aperture, and a plurality of interlocking eccentric members, within said rigid member, provided with a pivot point adapted to be adjusted by inter-movement of said eccentric members.

3. An adjustable pivot, comprising a rigid member, and a member interlocking with said rigid member and detachable therefrom and provided with a pivot point adjustable in any plane perpendicular to the axes of the members and with respect to said rigid member.

4. An adjustable pivot, comprising a rigid member, and a plurality of eccentric members interlocking with each other and with the rigid member, one of said eccentric members being provided with a pivot point adapted to be adjusted by the intermovement of said eccentric members, and in respect to the rigid member.

In testimony that I claim the foregoing as my invention, I have signed my name in presence of two subscribing witnesses.

GUSTAV BENISCH.
